CLAIM

The ornamental design for a cowling for an outboard marine engine, as shown and described.

DESCRIPTION

FIG. 1 is a perspective view of a cowling for an outboard marine engine showing our new design.

FIG. 2 is a side view thereof.

FIG. 3 is an opposite side view thereof.

FIG. 4 is a front view thereof.

FIG. 5 is a rear view thereof.

FIG. 6 is a top view thereof; and,

FIG. 7 is a bottom view thereof.

The broken lines in the drawings illustrate portions of the cowling that are not part of the claimed design.
